US00D987650S

(12) **United States Design Patent** (10) **Patent No.:** **US D987,650 S**
(45) **Date of Patent:** **** May 30, 2023**

(54) **STAND FOR VIDEO CONFERENCING DISPLAY**

(71) Applicant: **LG ELECTRONICS INC.**, Seoul (KR)

(72) Inventors: **Hyeyoung Hong**, Seoul (KR); **Yongho Lee**, Seoul (KR); **Hongseok Kim**, Seoul (KR)

(73) Assignee: **LG ELECTRONICS INC.**, Seoul (KR)

(**) Term: **15 Years**

(21) Appl. No.: **35/513,101**

(22) Filed: **Jun. 10, 2021**

(80) **Hague Agreement Data**

Int. Filing Date: **Jun. 10, 2021**
Int. Reg. No.: **DM/214822**
Int. Reg. Date: **Jun. 10, 2021**
Int. Reg. Pub. Date: **Dec. 10, 2021**

(30) **Foreign Application Priority Data**

Dec. 18, 2020 (KR) 30-2020-0063307

(51) **LOC (14) Cl.** **14-02**

(52) **U.S. Cl.**

USPC **D14/451**; D19/114

(58) **Field of Classification Search**

USPC D6/300; D14/203.8, 239, 302, 375–377, D14/432, 448, 451; D19/113, 114
CPC G09F 15/0056; G09F 1/14; A47B 97/04; A47B 2097/006

(57) **CLAIM**

The ornamental design for a stand for video conferencing display, as shown and described.

DESCRIPTION

1. Stand for video conferencing display

1.1 : Perspective

1.2 : Front

1.3 : Back

1.4 : Left

1.5 : Right

1.6 : Top

1.7 : Bottom

1.8 : Second Perspective, showing the stand for video conferencing display in a potential state of use

1.9 : Third Perspective, showing the stand for video conferencing display in a potential state of use

The broken lines depicting a video display screen in reproductions 1.8 and 1.9 represent environmental subject matter that forms no part of the claimed design.

1 Claim, 9 Drawing Sheets
